ISAAC PATRICK, OF NEW YORK, N. Y., ASSIGNOR TO E. W. BLISS COMPANY, OF NEW YORK, N. Y., A CORPORATION OF WEST VIRGINIA.

COMPENSATOR OR RESISTANCE FOR PRESS PARTS.

Application filed August 1, 1924. Serial No. 729,662.

To all whom it may concern:

Be it known that I, ISAAC PATRICK, a citizen of the United States of America, residing in the borough of Queens, city and State of New York, have invented certain new and useful Improvements in Compensators or Resistances for Press Parts, of which the following is a specification.

This invention relates to power presses and analogous machines in which it is required to compensate the weight (or other thrust) of a moving part, and in which it is desirable to restrict the compensating means within limited dimensions.

10 The invention is particularly adapted to power presses having a vertically-reciprocating member, such as a press head, punch slide, or blank-holder slide. In some presses it is possible to wholly or partially counter-balance such reciprocating member by another reciprocating member the weight of which constitutes a sufficiently effective compensator, but for rapidly-acting presses where it is desirable to minimize the moving 15 masses, it is preferable to employ compensating springs. The difficulty in the use of such springs has been that they require to be made of considerable length, and commonly reach dimensions which exceed the vertical 20 limits available. Experience shows it to be good mechanical practice to make the spring of a length approximately twelve times the maximum compression, which, for a stroke of say ten inches, requires a spring of about 25 ten feet long, which in many cases would extend the press to a prohibitive height. The present invention provides for such spring-compensating means as will materially reduce the vertical dimension required 30 therefor.

According to the present invention the compensating means comprises a plurality of springs of equal or approximately similar resilience arranged parallel so as to come (wholly or to a substantial extent) within the same vertical dimensions, and connected serially from bottom to top, so that the thrust due to the compensated weight is transmitted serially from one 35 spring to another. Preferably the springs are of equal or nearly equal resilience, and for greater compactness these springs are preferably nested one within the other. Preferably the springs act by compression,

their intervening connecting means being 40 consequently under tensional stress.

The accompanying drawings illustrate two embodiments of the invention as applied to two different forms of power presses.

Figure 1 is an elevation of a press as a 45 whole;

Fig. 2 is a view on a larger scale, showing one set of the springs and their appurtenances in vertical section;

Fig. 3 is a vertical transverse section 50 showing one of the pair of spring compensators partly in vertical transverse section, and the other in elevation;

Figs. 4 and 5 show the invention as applied to a spring-supported slide or table, or 55 yielding bed, Fig. 4 being an elevation partly broken away in vertical section, and Fig. 5 a transverse section on the line 5—5 in Fig. 4.

Referring first to Figs. 1, 2, and 3, A 60 designates any suitable construction of fixed framework, such as are commonly provided in power presses, and comprising a base *a*, upright side or end frames *b*, *b*, and a top frame or crown *c*. *B* is a vertically-movable 65 slide or head, the weight of which it is desired to compensate. *C* is, as a whole, the compensating means. This means consists essentially of springs *D* and *F*, with an intervening connecting means *E* whereby to 70 transmit the thrust from one spring to another. The springs *D* and *F* are preferably 75 nested one within the other, as shown, and are preferably of equal resilience, or as 80 nearly so as is practicable, in order that under a given stress they shall yield equally. The respective springs may, if desired, be 85 made each of two or more sections connecting through intervening rings *d*, *e*, this being a convenient construction, but not essential. The springs are shown as compression 90 springs, one of them reacting against any fixed abutment, and the other reacting directly or indirectly against the slide *B*. In the specific construction shown, the outer 95 springs *F* are seated on fixed abutments *f*, *f*, connected in any suitable manner to the crown *c* or any other convenient part, as, for example, by suspension rods *g*, *g*, hung by nuts *g'* from a head *h* mounted on the 100 crown *c*. The opposite ends of the inner 105 springs *D* react against movable plates *i* connected in any suitable manner to the

slide B, as, for example, by means of tie rods *j*, *j*. Other connecting means may be substituted.

The intervening connector E between the springs of each pair is shown as comprising a tubular portion *k* having at its upper end an outward flange *l* overlying the top of the spring F, and at its lower end an inward flange *m* underlying the bottom of the inner spring D. The flange *m* is shown as in-turned and reinforced; the upper flange *l* is shown as united to the tubular portion by a screwthread; other details of construction may, however, be substituted.

In Figs. 1 to 3, inclusive, the slide B is shown in its upper position; as it descends, it pulls down the plates *i* and compresses the springs, so that the portion of each spring shown as projecting beyond the other is approximately taken up, so that at maximum compression the inner and outer springs occupy substantially the same vertical dimension. Thus a high degree of vertical compactness is attained. The clearance between the springs and the intervening tubular connecting portion *k* should be sufficient to avoid any sliding contact, but if necessary the portion *k* may be lubricated and caused to serve as a guide for keeping the springs in longitudinal alignment.

Figs. 4 and 5 show a modified and somewhat simpler construction. Here the member A' is a fixed bed from which is hung by tie rods *n*, *n*, a fixed yoke A² forming an abutment against which the outer springs F react. The part to be subjected to spring stress is a slide or movable bed B' which is movable within the enclosing base A', and which rests directly on the upper ends of the inner springs D, D. The slide B' may form a resistant support for a die which yields downwardly during the stroke of an upper die or punch against it, and for this purpose it is overlaid by a fixed plate G above which such die or other part may be mounted and connected to the spring-pressed slide B' by any suitable connections, such as by movable pins H, H, passing freely through holes in the plate G. Any desired initial stress may be given to the springs in the uppermost position of the slide B' by drawing up the abutment frame A² by nuts *p*, *p*. The intervening spring connector E, as here shown, is of essentially the same construction previously described. The springs D, F, are each single springs, instead of being made up of two or more sections. The operation is essentially the same as before described. The springs E, F, are shown in Fig. 5 as arranged in pairs, and in Fig. 4 is shown a multiple arrangement of four pairs giving eight compound springs. By this means an extremely stiff spring bed may be provided, capable of a considerable descending movement, while its

springs occupy very limited vertical dimensions.

It will be understood that the invention may be considerably modified in construction without departing from its essential features. The invention is not limited to the use of springs in compression, nor to the nesting of springs one within the other. The construction may be considerably varied within the scope of the appended claims.

I claim as my invention:—

1. In a power press having a reciprocating member, a compensating means therefor comprising a plurality of springs of similar resilience arranged with a substantial overlap in direction of stress and connected to transmit thrust serially from one to the other. 80

2. In a power press having a reciprocating member, a compensating means therefor comprising a plurality of springs of similar resilience arranged parallel within similar dimensions, and an intervening connection extending parallel to the springs for transmitting thrust serially at all times from one to the other. 85

3. In a power press having a reciprocating member, a compensating means therefor comprising springs of similar resilience nesting one within the other and connected to transmit thrust serially from one to the other. 95

4. In a power press having a reciprocating member, a compensating means therefor comprising springs of similar resilience nesting one within the other, and an intervening connection from one end of the inner spring to the opposite end of the outer spring within the space between the nested springs. 100

5. In a power press having a reciprocating member, a compensating means therefor comprising springs of similar resilience nesting one within the other, and an intervening connection between said springs formed as a tube enclosing the inner spring and within the outer spring, and having end flanges abutting the ends of the respective springs. 110

6. In a power press having a vertically reciprocating member, a compensating means therefor comprising a plurality of springs arranged parallel within similar vertical dimensions, and having a parallel intervening connection for transmitting thrust serially from one to the other, a fixed abutment against which one spring reacts, and a movable abutment receiving the thrust of the other spring, and a tie member connecting the latter to said reciprocating member of the press. 115

In witness whereof I have hereunto signed my name.

ISAAC PATRICK.
